Attorney

UNITED STATES PATENT OFFICE.

GORDON H. KEENEY, OF SACRAMENTO, CALIFORNIA.

CARD HOLDER.

Application filed September 23, 1926. Serial No. 137,282.

This invention relates to a novel card holder used more particularly in playing the game of duplicate bridge.

This particular type of bridge, commonly known as duplicate bridge, is a variation of the ordinary game of bridge, it being essential that the hands, as dealt, be kept intact and replayed in proper group order in accordance with the rules of the game.

10 The invention relies more particularly for its novelty on the particular construction of the holder, wherein the same is formed from a single block of material recessed in a special way for providing four different compartments for the books and different hands dealt.

Other features and advantages will become apparent from the following description and drawings.

20 In the drawings:
Figure 1 is a perspective view of the holder,

Fig. 2 is a section taken approximately upon the plane of the line 2--2 of Fig. 1,
25 Fig. 3 and Fig. 4 are perspective views of the details.

Referring to the drawings it will be seen that the reference character 1 designates the body preferably in the form of a rectangular block of appropriate material. In accordance with the invention, this block is formed in two grooves or recesses opening through opposite longitudinal edges and also opening through the ends. In other words, 30 the block is cut inwardly from opposite longitudinal edges to form two duplicate pockets. The bottom of the pocket in each instance terminates in close proximity to the adjacent longitudinal edge portions. More-

over, a central partition strip 2 is fitted into each pocket for dividing it into two compartments for reception of the individual groups or hands of cards. Also fitted in the ends of the pockets are strips 3 which serve to close the ends and to complete the compartments. Each compartment is provided with a finger notch 4 and a cooperating finger depression 5 which serve to facilitate removal of the cards in an obvious manner.

The gist of the invention, as before stated, is in the simplified method of manufacture of the improved device which simply comprises an oppositely recessed block having small strips fitted into the same to form individual card compartments. If desired, the spaced relationship of the block may be provided with appropriate indicating characters.

Undoubtedly, persons familiar with the large game of bridge, and particularly the type known as duplicate bridge, will understand the method of use of the holder and will appreciate its advantages and features. In view of this, a more detailed description is thought unnecessary.

I claim:

A card holder comprising a single block having recesses cut therein from opposite longitudinal edges, a central partition strip fitted into each recess, and end strips fitted into the end portions of the recesses, dividing them into individual card compartments each compartment being provided with finger notches to facilitate removal of the cards.

In testimony whereof I affix my signature.

GORDON H. KEENEY.
